FOOTBALL BLOCKING DUMMY OR SIMILAR ARTICLE

Harold W. Kopp, Saxonville, Mass., assignor to Halko,
Inc., Saxonville, Mass., a corporation of Massachusetts

Filed Oct. 12, 1965, Ser. No. 87,439

Term of patent 14 years

(Cl. D34—5)

FIG. 1

FIG. 2

I claim:

The ornamental design for football blocking dummy or similar article, substantially as shown and described.
